BY

Charles C. Gill,
ATTORNEY.

UNITED STATES PATENT OFFICE.

FRANK G. DELBON, OF BROOKLYN, NEW YORK.

DESIGN FOR A SHOE HEEL.

60,219.

Specification for Design.

Patented Jan. 17, 1922.

Application filed November 20, 1920. Serial No. 425,574. Term of patent 14 years.

To all whom it may concern:

Be it known that I, FRANK G. DELBON, a citizen of the United States, residing at Brooklyn, in the county of Kings and State of New York, have invented a new, original, and ornamental Design for a Shoe Heel, of which the following is a specification, reference being had to the accompanying drawings, forming a part thereof, and in which—

Fig. 1 is a bottom view,

Fig. 2 a side elevation, and
Fig. 3 a front edge view of a shoe-heel embodying my design.

I claim:
The ornamental design for a shoe-heel, as shown.

FRANK G. DELBON.
